WALL PAPER.**

No. 20,221.

Patented Oct. 21, 189

UNITED STATES PATENT OFFICE.

CHARLES BOOZE, OF BUFFALO, NEW YORK, ASSIGNOR TO M. H. BIRGE
& SONS, OF SAME PLACE.

DESIGN FOR WALL-PAPER.

SPECIFICATION forming part of Design No. 20,221, dated October 21, 1890.

Application filed September 27, 1890. Serial No. 366,374. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying photograph, forming part thereof.

The leading feature of my design consists of sprays or small bunches of roses disconnected and arranged in a wavy line between light parallel lines arranged horizontally upon a light background, with a row of leaves arranged regularly and uniformly between the parallel lines and the sprays of roses, forming an ornamental border, as represented in the accompanying photograph. At a short distance above the top of the ornamental border are ar-

ranged two light horizontal lines running parallel with the top of the border, and at about an equal distance from the bottom of the ornamental border is arranged a light line running parallel with the border, and at a suitable distance below this line is arranged a group of parallel lines. 20 25

My design is more particularly used and designed for a ceiling decoration or border.

What I claim is—

The design for wall-paper herein shown and described. 30

Witness my hand this 13th day of September, 1890.

CHARLES BOOZE.
